UNITED STATES PATENT OFFICE.

SAM ARNOL GOTTL, OF SAN FRANCISCO, CALIFORNIA.

STEAM-APPLYING DEVICE.

Application filed December 8, 1923. Serial No. 678,291.

The present invention relates to improvements in means for applying steam to cloth material for the purpose of revivifying the same, and is particularly intended to be used for cloth that cannot be conveniently pressed or that loses its original appearance when pressed by the ordinary methods. It is principally proposed to use my device for the treatment of crepe material. The latter material when new, is crinkled and it is this crinkle which gives life to the material and that particular appearance producing a much desired aesthetic effect. When the material is pressed by ordinary methods it loses its crinkle and becomes practically smooth. My device is designed for the purpose of allowing such material to be treated without losing its crinkle and also allows the crinkle to be restored where it has been lost. My device comprises a means for allowing diffused steam to be discharged against the material from a distance of say a few inches while the material is freely suspended from a hanger or the like or disposed on a model in a show window. For this purpose I provide a steam diffusing element that is very light so that it may be conveniently handled all day long and may be disposed in any desired position, with the discharging bottom presented downwardly or sideway or upwardly as the occasion may require. My device may also be used to advantage for raising the nap on velvet material and for similar purposes.

The preferred form of my device is illustrated in the accompanying drawing in which Figure 1 shows a vertical longitudinal section through the same; Figure 2 a vertical transverse section taken along line II-II of Figure 1; and Figure 3 a horizontal section taken substantially along line III-III of Figure 2. While I have shown only the preferred form of the invention it should be understood that various changes or modifications may be made within the scope of the claims hereto attached without departing from the spirit of the invention.

My device includes a steam chest (1) preferably of rather flat formation and resembling in its shape the form commonly used for pressing irons. A pipe (2) extends into the chest preferably from the rear end (3) thereof, which forms a loop in the steam chest and leaves the same through the rear wall as shown at (4). When the device is in use steam is circulated through this pipe con-

tinuously in any suitable manner. On the top of the steam chest are provided two standards (5) supporting a handle (6) in parallel relation to the steam chest. The loop of the pipe (2) extends slightly forwardly of the handle and is provided with a valve mechanism (7) of any suitable construction controlling a port (8) through which steam may enter into the steam chest when the valve is opened. The valve is actuated by means of a rod (9) extending upwardly in a housing (11) and is normally closed by means of a spring (12) but may be opened by the manipulation of a short lever (13) pivoted in the front end of the handle (6) as shown at (14) and arranged in such a manner that the same may be readily actuated by the thumb of the hand holding the handle (6).

The bottom (16) of the steam chest is arched in the manner shown in the drawing so as to present a concave face and is provided with a large plurality of perforations (17). A cloth (18) of a material allowing steam to freely pass therethrough such as unbleached muslin is stretched over the hollow or concave bottom and held in place by means of a band (18') clamping the same against the lower portion of the steam chest wall. Above the arched bottom of the steam chest is provided a plate (19) of corrugated material preferably presented in slanting position and formed with perforations (21) in the ridges of the corrugated material. The plate stops short of the rear end of the steam chest and is turned downwardly as shown at (22) to form a small vessel (23) for the products of condensation, which latter may be removed from time to time through the valve controlled port (24).

The manner of using my device is as follows: Steam is continuously circulated through the loop (2). The operator takes hold of the device by means of the handle (6) controlling with his thumb the lever (13) operating the valve mechanism (7) and moves the device past the dress to be treated, with the cloth surface confronting the material but remaining spaced therefrom, say from one to three inches, the dress being suspended from a hanger. Steam then enters the steam chest (1) and passes through the perforations (21) in the plate (19) and the perforations (17) in the arched bottom (16) and finally through the cloth (18), which latter is directed against the mate-

rial to be treated. During the initial period while the device is still cool a certain amount of the steam will condense in the steam chest and is carried off in the grooves of the corrugated deflecting plate into the receptacle (23) from where it may be withdrawn from time to time through the valve (24). If the device is well heated comparatively little steam will condense.

10 It has been found by actual experience that crepe and nap material respond very quickly to this treatment and that all wrinkles are removed immediately, while at the same time the crinkle in all crepe woven materials is restored immediately.

I claim:

1. Means for spraying diffused steam against suspended cloth material comprising a steam chamber, a cloth bottom for the same through which the steam may be directed against the material, a pipe passing

through the steam chamber having steam circulating therethrough and being perforated to allow steam to enter the chamber and a valve for the perforation in the pipe having means associated therewith for operating the same from the outside of the chamber.

2. Means for spraying diffused steam against suspended cloth material comprising a steam chamber, a cloth bottom for the same through which the steam may be directed against the material, a pipe passing through the steam chamber having steam circulating therethrough and being perforated to allow steam to enter the chamber and a corrugated plate interposed between the entering steam and the cloth bottom adapted to deflect products of condensation while permitting the steam to pass through perforations in the ridges thereof.

SAM ARNOL GOTT.
